COMBINATION BRAKE DRUM AND WHEEL

Richard E. Dexter, Elkhart, Ind., assignor to Dexter Axle
Company, Inc., Elkhart, Ind., a corporation of Delaware

Filed Jan. 2, 1968, Ser. No. 10,007

Term of patent 14 years

Int. Cl. D12—14

U.S. Cl. D14—30

Fig. 1

Fig. 2

Fig. 3

Fig. 4

FIGURE 1 is a perspective view of the external side of the combination brake drum and wheel, showing my new design;

FIGURE 2 is a front elevational view;

FIGURE 3 is a side elevational view; and

FIGURE 4 is a vertical cross sectional view, the section being taken on line 4-4 of FIGURE 2.

I claim:

The ornamental design for a combination brake drum and wheel, substantially as shown.
